(57) **CLAIM**

The ornamental design for a coaxial electrical connector, as
shown and described.

DESCRIPTION

FIG. 1 is a front view of a coaxial electrical connector showing
my new design;

FIG. 2 is a rear view thereof;

FIG. 3 is a left side view thereof, wherein a right side view
thereof is symmetrical to the right side view;

FIG. 4 is a plan view thereof; and

FIG. 5 is a bottom view thereof;

FIG. 6 is a perspective view thereof;

FIG. 7 is another perspective view thereof; and,

FIG. 8 is a cross sectional view thereof in the direction of line
8-8 of FIG. 1.
